ANTI-BACK-DRAFT DAMPER

Paul R. Jordan, Indianapolis, Ind.

Application October 1, 1938, Serial No. 232,768

3 Claims. (Cl. 98—119)

This invention relates to an anti-back-draft damper which is particularly applicable for use in ventilating flues in a system in which the air in the room to be ventilated is maintained under a slight static pressure and is discharged through said flue as a result of said pressure.

The general object of a back draft damper in such a system is to prevent inflow of air through the flue when the desired pressure in the ventilated room is not maintained. A secondary object of such dampers is to equalize the removal of air when a number of flues are used to exhaust the air from a single room or group of connecting rooms.

One object of the present invention is to provide a back draft damper which can be installed in a flue with a minimum of time and expense.

Another object is to provide a back draft damper which may be installed in a flue already constructed without additional masonry work being required.

Another object of the invention is to provide an anti-back-draft damper which is economically manufactured and may be sold and installed at a low cost.

Another object of the invention is generally to improve the construction and functioning of anti-back-draft dampers.

Other objects and features of the invention will be understood from the accompanying drawings and the following description and claims:

Fig. 1 is a sectional view of a flue having installed therein an anti-back-draft damper constructed in accordance with the invention. Fig. 2 is a perspective view of the stationary parts of the damper construction. Fig. 3 is a fragmentary view of a damper blade and associated parts. Fig. 4 is another view of the same taken in the direction indicated by the arrow 4 of Fig. 3. Fig. 5 is another view of the same taken in the direction of the arrow 5 of Fig. 3.

In the drawings there is indicated a flue 10 which is assumed to be rectangular in shape and is provided with walls 11 and 12. The normal direction of air movement is upward as indicated by arrows 13. In Fig. 1 there is shown installed in said flue a preferred form of the invention which includes a stationary rectangular frame 14. Said frame is preferably formed of angle irons, the lower legs 15 of the angles extending inwardly as shown in Fig. 2. The frame 14 has one dimension greater than the corresponding inside dimension of the flue and may thus be placed in the angular position shown in Fig. 1 with the lower edge resting upon a support 16 and the upper edge

resting against the opposite inner wall of the flue. The support 16 may be in the form of one or more bolts inset in the wall 11 of the flue or a number of nails may be driven into the mortar joints of the flue for the same purpose. Other forms of support may be used.

In conjunction with the frame 14, there is provided a damper blade 17 preferably formed of sheet metal with an offset portion 18, an upwardly extending portion 19 and a downwardly 10 extending portion 20 of smaller area than the portion 19. The portions 19 and 20 lie in substantially parallel planes. A reinforcing angle 21 is secured to the rear surface of the portion 19 and extends over the major part of the portion 20 and 15 is secured thereto by a spacer member 22. A counterweighting angle 23 is secured to the lower edge of the portion 20 and serves approximately to equalize the moments of inertia of the portions of the blade on either side of the offset 18. 20

Adjacent the edges of the blade there are provided bearing members 24 and 25 secured by bolts 26 to the offset portion 18 of the blade. Bearing member 25 carries a knife edge 27 extending beyond the edge of the blade. Bearing 25 member 24 carries a knife edge notch 28. The frame 14 has secured on opposite sides thereof a pair of bearing members 29, each of which is provided with a hole 30 for reception of the corresponding bearing members 24 and 25. 30

A balancing rod 31 passes through a suitable opening in the offset portion 18 of the blade and is secured thereto by lock nuts 32.

In the assembly of the damper proper, the blade is first assembled without the bearing members 24 and 25. Said blade is then introduced into the frame 14 by means of openings 33 provided in the lower legs 15 at each side of the frame adjacent the bearing members 29. The bearing members 24 and 25 are each engaged with the corresponding bearing members 29 and are then secured to the blade by the bolts 26. The notch 28 prevents lateral movement of the blade. The frame 14 is then placed at an angle corresponding to that which it will assume in the flue and the adjusting rod 31 is adjusted so that the blade 17 will lie flat within the frame 14 when there is no difference of pressure on the opposite sides of the blade but will assume an upright position as shown in Fig. 1 when there is a slight excess of 50 pressure on the undersurface of the blade. In order to prevent noise of operation in the closing of the damper there is provided on the upper surface of the angle leg 15 above the bearing members 29, a strip 34 of felt or similar cushioning 55

material. A similar strip 35 is provided on the under surface of that portion of the leg 15 below the bearing member 29. It will be obvious that when the damper is closed, the upper portion 19 thereof engages the strip 34 and the lower portion 20 thereof engages the strip 35. A stop member 36 is secured to the frame 14 as best shown in Fig. 2 and serves to limit the opening of the damper.

10 The completely assembled damper construction may then be inserted in the flue and is usually passed upwardly therein beyond the support 16. The frame 14 is then tilted to bring its lower edge against the support 16 and the opposite edge is brought to rest against the opposite wall of the flue. Thus, in the installation of the damper, no masonry work of any kind is required. Furthermore, no accurate sizing of the flue or the frame 14 is necessary since the angle of inclination is not critical within several degrees. The whole operation of placing the damper in the flue may be accomplished in a small fraction of a minute.

15 When once installed, a loss of pressure in the ventilated room which might result in a down draft of air in the flue immediately results in the closing of the damper. A subsequent increase of the pressure acting on the larger area of the upper portion 19 of the damper blade serves to open the damper to its full open position against the stop 36. For equalizing the air flow through a number of related flues, the stop members 36 of their corresponding dampers may be suitably bent to adjust the full open positions of the individual dampers.

20 30 35 40 30 35 40 The provision of the adjusting rod 31 in the position shown insures that it may easily be reached from below for further balancing of the blade if necessary. For this purpose, the lower end of the rod 31 is provided with a slot 37 which may be engaged by a screw driver or other suitable tool.

The foregoing specification describes the in-

vention in one of its preferred forms of the details of which may be varied within wide limits by those skilled in the art without departing from the scope of the invention as defined in the appended claims.

5

The invention claimed is:

1. In combination with a flue, a damper frame having a draft opening therein, a support for an edge of said frame secured to a wall of said flue, said frame resting on said support and being inclined upwardly therefrom within said flue and having its opposite edge resting against the opposite wall thereof, and a damper blade pivotally mounted on said frame and adapted to close said opening therein. 10
2. In combination with a flue, a damper frame having a draft opening therein, a support for an edge of said frame secured to a wall of said flue, said frame resting on said support and being inclined upwardly therefrom within said flue and having its opposite edge resting against the opposite wall thereof, a damper blade having portions arranged in substantially parallel planes and an offset portion joining the same, a pair of detachable bearing members secured to said offset portion adjacent opposite edges of said blade, and mating bearing members carried by said frame and pivotally supporting said first mentioned bearing members. 15
3. In combination with a flue, a damper frame having a draft opening therein, a support for an edge of said frame secured to a wall of said flue, said frame resting on said support and being inclined upwardly therefrom within said flue and having its opposite edge resting against the opposite wall thereof, a damper blade pivotally mounted on said frame and adapted to close said opening therein, and an adjustable stop member attached to said frame and engaging said blade to define the limit of opening movement thereof. 20
